UNITED STATES PATENT OFFICE

2,387,009

RAIL FASTENING

Ralph P. Clarkson, Milford, Conn.

Application May 22, 1943, Serial No. 483,010

4 Claims. (Cl. 238—349)

My invention relates to rail fastenings and in particular to rail fastenings which comprise a resilient clip fulcrumed on the tieplate and pressed on the rail by the action of a holding member which is inserted in the present rail spike hole of the tieplate. The clip is preferably a sheared plate with a round hole punching for the holding member which is, preferably, a dog leg bolt, i. e., a bolt having a bent shank. One part of the bolt shank is threaded and the shank is of rectangular section below the threads and has an overall dimension in one direction which is greater than that of the spike hole or other opening into which it is to be inserted from the top. In the other direction, the rectangular section of the bolt has a dimension substantially that of a rail spike.

In many instances in present track, the base of the rail extends over the spike hole to a greater or less extent and it is difficult for a hook bolt inserted from the top with the rail in place to get sufficient grip below the tieplate under the rail in all instances met with along a stretch of laid rail with the variations that occur or, if constructed to get such a grip, it must be of reduced section or lie backwards at an angle or both, thus being limited in strength. I propose to provide a maximum of strength both of the holding bolt and of the clip and to provide the clip with sufficient resiliency without overloading the bolt and yet provide a rail fastening of universal application.

In the case of the bolt, I provide a maximum section through the use of a bent or dog leg shank such that the bolt may be inserted into the present tieplate opening from the top and then set upright and braced by the walls of the spike hole, at the same time being of minimum length and thus least likely to bend through rail lifting in wave motion after installation. Moreover, my preferred bolt is of full spike width and of such shape that it may hook under any side of the spike opening. That is, the bolt will hook under the back edge or the side edge of the spike hole equally well as the front or rail edge, thus being of general utility, particularly effective and convenient with tieplates having bottom ribs or waffle construction.

In the case of the clip or plate spring, the bolt hole punching is made, preferably, as a round hole, thus upsetting, crystallizing or distorting a minimum area around the hole and providing no sharp corners, lines or shear drag along which breakage may take place at this point. Also, I prefer to form the clip in such manner as to pro-

vide two resilient arms, one of which is engaged by the bolt and the other by the rail, there being yielding action between them for a portion of the length of the clip, the arms being joined together at a point between the fulcrumed back edge of the clip and the point of applied bolt pressure, the back or tieplate end of the clip being of relatively great stiffness. By this construction it is possible to bring the point of pressure on the rail nearer to the holding bolt and thus maintain a high rail pressure yet with a safe bolt pressure, as will be later apparent.

It is an object of this invention to provide an improved rail fastener, simple and rugged in design, easy to manufacture and of general application to present track structure utilizing the standard spike holes when the rail spike is removed or omitted, or any similar opening, not necessarily at the edge of the rail.

Another object of my invention is to provide a rail fastener which maintains yielding vertical pressure on the rail of such magnitude as to frictionally restrain longitudinal creeping of the rail without undue stress in the fastener.

A further object is to provide a rail fastener in which the bolt is of maximum adaptability and the clip of such nature as to give desirable rail pressures without overstress of the bolt.

With the foregoing and other objects in view, as will be apparent to those skilled in the art as the description proceeds, my invention resides in the combination and arrangement of parts and in the details of construction described in this specification and particularly pointed out in the appended claims, it being understood that changes may be made in the particular embodiment of the invention within the scope of what is claimed without departing from the spirit of the invention. I intend no limitation other than those of the claims when fairly interpreted in the light of the full disclosure and the present state of the art.

Referring now to the accompanying drawing illustrative of my invention and showing an embodiment thereof at present preferred:

Fig. 1 is an elevational assembly view, fragmentary and partly in section, showing the application of a preferred form of rail fastener embodying my invention; Fig. 2 is a perspective sketch illustrative of the clip shown in Fig. 1; Fig. 3 is an elevational view of a modification of the clip of Fig. 2; Fig. 4 is a view, similar to that of Fig. 1, showing the application of another form of clip with the bolt of Fig. 1; Figs. 5 and 6 are side and front views, respectively,

of the holding member of Fig. 1; Fig. 7 is a perspective sketch of a modification of the clip of Fig. 2; Fig. 8 is a section on the line 8-8 of Fig. 5; Fig. 9 is an elevational view similar to that of Fig. 1, showing the method of insertion of the bolt of Figs. 5 and 6 from the top through the present spike hole of a tieplate; Fig. 10 is a view similar to that of Fig. 1 showing the engagement of the holding bolt at the side of the tieplate opening, the tieplate having interfering bottom ribs, a modified form of clip being shown; Fig. 11 is a perspective sketch of the clip of Fig. 10; Fig. 12 is a view similar to that of Fig. 1 showing the application of a modified form of the clip of Fig. 1, using another form of holding member.

Like reference characters refer to like parts in all the views.

In the embodiment of my invention illustrated (Fig. 1), a rail 10 is resting on and supported by a tieplate 9, in this instance shouldered, both rail and tieplate being shown fragmentary. The usual spike opening 8 is shown here adjacent to the rail. To clamp the rail to the tieplate and frictionally hold same, a rail fastener is provided comprising a clip 7 and a holding bolt 6 positioned in the rail spike hole 8, the bolt 6 having a hook or lip portion 5 engaging the underside of the tieplate 9. In this assembly, a preferred clip 7, shown in detail in Fig. 2, rests its rear or back end on the tieplate 9, thus providing a fulcrum for the pressure action of a bolt 6 when a nut 4, threaded thereon, is pulled up or tightened. Clip 7 is provided with a bolt opening 3, preferably a round punching for the reasons set forth above, said bolt opening 3 being made in an arm 2 which is resiliently related to the remainder of the clip 6, particularly the forward or rail-bearing portion thereof 1 which presses upon the rail base.

Clip 7 is, in this instance, a bowed plate of resilient material, preferably having a center portion struck up to form an arm 2 (Fig. 2) but it is shown that a similar arm 2a may be struck up from the side of a clip 7a (Fig. 7) providing a resiliently coacting rail arm 1a. Moreover, other forms of clips embodying my invention are shown as, for example, a clip 13 (Fig. 3) in which the tieplate end of the plate is laminated or folded upon itself for a portion of its length and then separated into a bolt pressure arm 12 and a rail arm 11; a clip 1b (Figs. 10 and 11) in which a bolt arm 2b may be downwardly struck and a resiliently coacting rail arm 1b formed. Moreover, if desired, the bolt opening of the clip may be punched with a dependent tongue 16 (Fig. 12) when a clip 7c is to be used with a bolt 6a having a dimension less than that of the tieplate opening. Such tongue and bolt construction are shown and claimed in my Patent No. 2,203,624 of June 4, 1940.

In the present invention a preferred characteristic of the clip is the division thereof into separate coacting resilient arms, one of which is provided with an opening for the holding member and the other constructed to bear on the rail base. In the clips illustrated the effective length of the rail bearing arm is greater than that of the bolt arm and thus of greater resiliency, if of comparable section, the two arms being joined behind the bolt opening and fulcrumed at the back end of such joined portion on the tieplate. This construction may provide equal rail base pressure as that of an undivided clip 15 (Fig. 4) applied to a rail 10

and held by a bolt 6, equal or greater resiliency of the rail arm but with less bolt pressure, as the rail pressure (Fig. 1, for example) is applied to the rail nearer to the edge of the rail and thus closer to the bolt. The rail arm 1 (Fig. 1) may be of the same effective length from its rail contact point back to its junction with the bolt pressure arm 2 as is the effective rail arm of clip 12 (Fig. 4) from its rail contact point to the point where it is held by the nut 4. The ratio of the lever arms in the construction of Fig. 1, however, is such that the bolt pressure more nearly approximates that on the rail than is the case in Fig. 4. Similar in this respect are the clips of Figs. 3, 7, 11, and 12, also.

Special mention is made also of the novel construction of the holding bolt 6 having a width (Fig. 6) equivalent to that of a rail spike and provided with a bent or dog leg shank (Fig. 5), the lower portion sloping at an angle to the threaded portion, resulting in offsetting the center line of the threaded portion from the center line of the hole.

The upper face of the sloping portion of the shank is indented to form a lip 5 to hook under the tieplate and at the same time to provide the adjacent spike hole bearing portion just above the lip. The overall width of the bolt, shown in Fig. 4, is greater than that of the spike hole by the amount of the projection of the hook. Moreover, by maintaining the full thickness of the bent portion (Fig. 5) the flat back of the bolt is brought below the inside bend line and provides a substantial bearing against the side of the tieplate opening opposite to the hook, whether it be the back of the spike hole (Fig. 1) or the side (Fig. 10), the latter arrangement being resorted to because of the ribs 14, 14, on the under side of the tieplate 9a.

Insertion of a bolt 6 into a spike hole 8 from the top requires (Fig. 9) insertion of the lower dog leg with the threaded portion pushed over but gradually straightening up as the lip 5 gets beyond the critical lower edge of the tieplate 9. The bolt is then brought into position (Figs. 1, 4, and 10), the clip slipped over the bolt, the nut threaded on and turned up to the desired pressure, normally of the order of 2500 pounds on the rail.

The offset of the bolt away from the rail (Fig. 1) relative to the near position of the usual hook bolt to the rail (Fig. 12) requires a greater force applied to the bolt to give the same rail pressure. Hence, for this form of bolt (Figs. 5 and 6) to be most effective, it is desirable to use a clip with a short rail arm to more nearly equalize bolt and rail pressures. To shorten the rail arm of such a clip as 15 (Fig. 4) decreases its flexibility under wave action of the rail and incident tieplate bending. Thus clips of the construction shown in Figs. 1, 3, 7, 11, for example, wherein the flexibility of the rail arm may be maintained, may be of particular value in combination with the bolt of Figs. 5 and 6.

65. What I claim is:

1. In a rail fastening device for resiliently clamping a rail to a tieplate characterized by the use of the regular tieplate spike hole for the holding member and the employment of a plate type spring clip resting at its rear end on the tieplate outwardly from the spike opening and at its front end on the sloping base of the rail and thus tending to bend the holding member away from the rail, a holding member of substantially rail spike width and of a shank thickness mater-

rially less than the corresponding spike hole dimension, insertable from above downwardly through the spike hole and provided with a dog-leg shank having flat side portions to bear against the four walls of the spike hole, the two flat side portions on the front and back sides of the holding member being parallel to but offset from each other, that at the front side being positioned to bear at the lower end of the spike hole wall and that at the back side being positioned to bear at the upper end of the opposite wall, the portion of said holding member between said two flat side portions when in operating position sloping at an angle across the spike hole to form a brace against the bending tendency of the spring clip, the center line of said holding member being offset from the center line of the spike hole, a portion of said holding member extending beneath and engaging the bottom of said tie-plate.

2. A rail fastening for resiliently clamping a rail to a support including a tieplate, said rail fastening comprising a resilient plate member fulcrumed at the back on said tieplate and resting at the front on said rail, an arm punched from the body of said plate member therebetween provided with an opening therethrough for

the passage of a holding member, said punched arm being joined to said body behind said opening away from the rail end and a holding member engaging said support and so constructed and arranged as to flex said resilient arm and thereby clamp said plate member down on the rail.

3. As an article of manufacture, a rail fastening element comprising a plate of resilient material having a rail-bearing end and provided with an arm punched from the body of said plate, said arm being provided with an opening for the passage of a holding member and joined to the body of said plate behind said opening away from the rail-bearing end.

4. As an article of manufacture, a rail fastening element comprising a clip of resilient material provided with a rail-bearing end and a tie-plate-bearing portion, an arm punched from the body of said clip therebetween and diverging from the rest of said clip and having an end free to flex provided with an opening near said free end, said arm being joined to the body of said clip behind said opening away from the rail-bearing end.

RALPH P. CLARKSON.
